UNITED STATES PATENT OFFICE.

MARION R. STOWELL AND JOHN E. STOWELL, OF PILLAGER, MINNESOTA.

SINGLE-DELIVERY MATCH-RECEPTACLE AND CIGAR-CUTTER.

960,431.

Specification of Letters Patent. Patented June 7, 1910.

Application filed July 14, 1909. Serial No. 507,595.

To all whom it may concern:

Be it known that we, MARION R. STOWELL and JOHN E. STOWELL, citizens of the United States, residing at Pillager, in the county of 5 Cass and State of Minnesota, have invented certain new and useful Improvements in Single-Delivery Match-Receptacles and Cigar-Cutters; and we do hereby declare the following to be a full, clear, and exact description of the invention, such as will enable others skilled in the art to which it 10 pertains to make and use the same, reference being had to the accompanying drawings, and to the letters and figures of reference 15 marked thereon, which form a part of this specification.

This invention relates to new and useful improvements in combined match safes and cigar cutters and comprises various details 20 of construction, combinations and arrangements of parts which will be hereinafter fully described and then specifically defined in the appended claim.

Our invention is illustrated in the accompanying drawings, in which:—

Figure 1 is a perspective view of the match safe. Fig. 2 is a transverse sectional view of the same. Fig. 3 is an end view showing the cigar cutter. Fig. 4 is a detail perspective view of the cigar cutting device. 30 Fig. 5 is an enlarged view in end elevation of the delivery cylinder. Fig. 6 is a side elevation of the delivery cylinder. Fig. 7 is an enlarged detail perspective view of the 35 cylinder, and Fig. 8 is a detail view of parts of two of the sides of the casing showing the manner of fastening the same together.

Reference now being had to the details of the drawings by letter, A, A designate two of the opposite sides of the receptacles which 40 may be made of any material suitable for the purpose and having slots A' formed therein at different locations adjacent to the marginal edge thereof for the reception of the lugs B projecting from the adjacent sides B' of the casing, said lugs being adapted to be passed through the slots and clenched, thus forming a secure means for holding the parts of the casing together.

50 Mounted in apertures in the opposite walls A of the casing are the spindle ends C of the delivery cylinder C', which cylinder has a longitudinal groove D formed therein of such a size as to receive a match, one end of 55 the groove being preferably somewhat

deeper than the other to compensate for the extra diameter of the head of the match.

Fixed to one spindle end of the cylinder is a hand wheel E forming means for rotating the cylinder and a spring E' is fastened 60 at one end to said stem and its other end to the casing and forming means whereby, as the cylinder is turned in one direction, the spring will be put under tension, said spring being of sufficient strength when under tension to cause the cylinder to return to its normal position after being released and after having delivered a match. The bottom of the receptacle, designated by letter H, has a shoulder H' formed upon the upper surface 65 adjacent to its forward end and against which a lug I projecting from the circumference of said cylinder is adapted to contact and form a stop to limit the rotary movement of the cylinder in one direction. 75

Mounted within the casing and diagonally disposed is a partition J, the lower end of which is recessed at J' for a purpose which will presently appear, and said partition forms a floor for the matches, indicated by 80 letter K, and being disposed at an inclination will cause the matches to roll down upon the circumference of the cylinder to be fed forward singly into a trough shaped recess H² formed in the projecting end of 85 the bottom H. Said partition J is secured in place preferably by means of lugs, as before described, that is by lugs which pass through apertures in the side walls and afterward clenched. Said lug I is adapted 90 to contact with the lower under edge of the inclined partition J to limit the rotary movement of the cylinder in its outer movement or in the act of delivering a match and the spring before described serving to return the 95 cylinder to its normal position.

The front wall of the casing, designated by letter O, has its lower end widened and slightly concaved upon its under face and fitting over the cylinder, leaving an opening 100 intermediate the lower end of said front partition and the recess H² through which the match is allowed to fall by gravity, as shown clearly in the sectional view of the drawings. 105

Mounted within the casing is a bell Q and rising from the bottom of the receptacle is a standard R upon which is pivotally mounted a lever R', serving as a hammer, one end of which is adapted to be thrown against 110

- the bell by the influence of a spring R^2 , which latter is put under tension as a partial rotary movement is given in one direction to the cylinder C' , causing the lug I to contact 5 with the lever and move the same upward against the tension of the spring. After the lug I passes the end of the lever, the spring will return the lever to its normal position and cause its opposite end to strike the bell 10 and give an alarm each time a match is delivered.
- Formed upon the circumference of the cylinder and at right angles to the groove therein are the cam projections T upon one 15 side of the groove and T' upon the opposite side of the groove, said cams T merging at corresponding ends into the circumference of the cylinder and their other edges inclining to and meeting the adjacent edge of the 20 groove. The cam projections T' terminate slightly more abruptly at the marginal edge of the groove than the cam projections T merging at their ends farthest from the groove into the circumference of the cylinder. Said projections serve to prevent the 25 matches from wedging between the lower portion of the wall O and the surface of the cylinder, allowing the same to be fed freely and singly.
- 30 Fastened to one of the spindle ends of the cylinder is a cutting knife S which is fixed thereto, and W designates a guard or housing fitting over the end of the spindle carrying said cutting knife and has an aperture 35 W' in the end thereof against the inner marginal edge of which aperture the knife is adapted to have a shearing action for the purpose of cutting the tip of a cigar inserted therethrough as the cylinder is given a forward rotary movement by the operator turning the wheel E .

The operation of our apparatus is simple and will be readily understood. The matches, being inserted in the casing upon 45 the inclined bottom J , will naturally feed by gravity to the cylinder. The cylinder is normally held in the position shown in the sectional view of the drawings by means of the spring. When it is desired to deliver a 50 match, the operator by taking hold of the wheel E and giving the same a partial rotary movement toward the front of the casing, a match which has previously fallen into the

groove of the cylinder will be deposited in the manner shown. During the forward rotary movement of the cylinder, the spring attached thereto is put under tension and serves to normally return the cylinder to its starting position when released. As the cylinder turns, the cutting knife in the end of the spindle will shear against the marginal edge of the aperture in the guard and serve as means for cutting off the tip of a cigar. As the cylinder turns forward, the lever R' is tilted and the spring R^2 put under tension 60 and, when the lug I passes the end of the lever R' , the spring R^2 will cause the lever R' to be thrown back to its normal position and the momentum of the tilting lever R' will cause its end to strike the bell and sound 65 an alarm, thus indicating that a match has been delivered.

By the provision of the circumferential cam projections which are in alinement with each other and at right angles to the groove 70 in the cylinder, the matches will be prevented from wedging and thus allowing the matches to fall singly into the groove.

What we claim to be new is:-

A single delivery match receptacle, comprising a closed casing provided with a delivery opening and an extension platform, the inner marginal wall of which is inclined and projects within the casing, inclined partitions positioned within the latter and having their lower edges notched and spaced apart, a rotatable, spring-actuated cylinder journaled in the opposite walls of the casing and provided with a longitudinal groove, which is held normally in alinement with the upper surface of one of said inclined partitions, cam ribs arranged in pairs in alinement with each other, one of each pair upon either side of the groove in alinement with each other, said cylinder adapted to turn in the space intermediate the partitions and the cam ribs to turn in said notches.

In testimony whereof we hereunto affix our signatures in the presence of two witnesses.

MARION R. STOWELL.
JOHN E. STOWELL.
